UNITED STATES PATENT OFFICE.

FREDERICK SAGER, OF ROCHESTER, NEW YORK, ASSIGNOR TO JAMES H. SAGER, OF ROCHESTER, NEW YORK.

MEANS FOR COOLING HOT BODIES.

No. 833,486.

Specification of Letters Patent.

Patented Oct. 16, 1906.

Application filed June 14, 1905. Serial No. 265,299.

To all whom it may concern:

Be it known that I, FREDERICK SAGER, of Rochester, in the county of Monroe and State of New York, have invented a new and useful Improvement in Means for Cooling Hot Bodies, which improvement is fully set forth in the following specification and shown in the accompanying drawings.

My invention is an improved means for conveniently and rapidly cooling heated bodies, as of metal, by increased or stimulated radiation, the invention being designed as an improvement on the device shown and set forth in Letters Patent No. 775,860, of date November 22, 1904.

It is well known and understood that heat will more rapidly radiate and become dissipated from surfaces or bodies through agencies, as projecting parts, having ample spaces or openings through which currents of air may freely circulate. With this fact in view I have aimed in my present invention to produce radiating devices having not only broad radiating surfaces, but also ample air-spaces through which currents of air may readily flow to convey away the outflowing heat.

Another object of my invention is to provide improved and better means for securing the radiating devices or radiators to the body to be cooled.

Other objects and advantages of the invention will be brought out and made to appear in the following description and the structure more particularly pointed out in the appended claims, reference being had to the accompanying drawings, which, with the reference characters marked thereon, form a part of this specification.

Figure 1 is a side elevation of a radiating element with a tool *k* shown by dotted lines. Fig. 2 is an elevation of the same seen as indicated by arrow in Fig. 1, a part being broken away and sectioned. Fig. 3 is a view of the outer end of the radiating element indicated by arrow 3 in Fig. 2. Fig. 4 is a view of the inner end of the radiating element indicated by arrow 4 in Fig. 2. Figs. 5 and 6 show, respectively, the end and the side of a holding divided ring. Fig. 7 shows a ball used with the ring. Fig. 8 shows the application of the radiating elements to a convex surface. Fig. 9 shows the radiating element applied to a flat surface. Figs. 10

and 11 show, respectively, a side elevation 55 and an end view of a slight modification in the form of the device. Fig. 12 shows a spiral form of the radiating element. Fig. 13 is a plan of a part of a plane or straight plate indented to receive the radiating elements in 60 rows, said radiating elements being represented by dotted lines and several of them sectioned at the surface of the plate. Fig. 14 shows a sheet-metal blank out of which to form a radiating element. Fig. 8 is drawn 65 to a scale smaller than that of the other figures.

In the drawings, A represents the radiating device in its preferred form, it consisting of a single piece of sheet-metal, as copper, made 70 primarily from a blank B, substantially as shown in Fig. 14. This metal blank is rectangular in form and centrally divided through its longer dimension by a kerf *a*, reaching from one end nearly to the opposite end, the two 75 parts *b* *b* at the sides of the kerf being transversely crimped or corrugated to form the radiating wings or portions C C, Figs. 1 and 2. The horizontal narrow strip or portion *d* uncut and at the end of the kerf *a* is bent to 80 form the cylindrical portion *e* of the radiating element, which bending of said part brings the corrugated portions *c* *c* opposite each other, as shown, with an ample air-space *f* between. These radiating elements are produced in quantities and designed to be attached side by side to the body to be cooled, the radiating elements when in place projecting at right angles from the surface. The 85 radiating elements may be attached to a 90 surface of any shape, plane or curved, Fig. 8 showing them as secured to the outer or convex side of a cylinder C and Fig. 9 showing them secured to a plane plate or body D.

I further aim in this invention to provide a 95 better and improved method or means for attaching or securing these radiating elements quickly and conveniently to the bodies to be cooled, this being accomplished for each radiating element by means of a split 100 ring *g*, Figs. 5 and 6, and ball *h*, Fig. 7, the diameter of the ball being slightly larger than the inner diameter of the ring. The body to receive the radiating elements is first 105 formed with a series of circular cavities or indentations *i*, Figs. 8, 9, and 13, preferably with conical bottoms, as shown, the diameters of the cavities being such as to freely

receive within them the cylindrical ends *e* of the radiating elements *A*. Previous to inserting a radiating element into a cavity it is loaded or supplied with a ring and ball, as shown in Figs. 2 and 3, the ball at this stage of the operation simply resting upon the upper end of the ring. All parts being in place, a single stroke of a hammer upon the end of a rod *k*, Fig. 15, placed in the radiating element and against the ball, as shown by dotted lines in Fig. 1, will drive the ball into the ring and expand the latter and the part *e*, causing said part to firmly press the inner circular wall of the cavity *i*, and so hold the radiating element firmly to place. The end of the part *e* of the radiating element rests against the conical bottom of the cavity, and when the ball is driven home to place, as stated, it also rests against the said conical bottom, as appears in Fig. 9, the center of the ball being substantially in the middle plane of the ring and below the surface of the plate or body. The tool *k* is of steel with its inner end preferably slightly hollowed to better fit the convex surface of the ball, the rod being inserted between the wings *c c* in a manner to be coaxial with the radiating element.

In the form shown in Figs. 10 and 11 the original blank metal sheet from which a radiating element is made is a long narrow strip with a perforation *l* at the middle. This blank strip is one-half the width of the blank *B* and twice the length and without the kerf, the corrugations being formed at the middle part of the strip equally on either side of the central opening *l*, the two ends of the strip being bent to semicylindrical forms and together constituting the cylindrical portion *m* for receiving the split ring and ball and to be inserted into a cavity *i* of the body, as in the case of the form of radiating element first described.

In the form shown in Fig. 12 a strip or ribbon of metal is wound in spiral form upon a mandrel of uniform diameter, this spiral body *E* being of indefinite length, and to subsequently cross-cut into radiating-element lengths. The diameter of the spiral body is not essential, it being shown as equal with the cylindrical parts *e m* of the other forms of radiating element and to fit the cavities *i* and to be set to place in the body to be cooled by means of the divided ring and ball

as in the other cases. The order of attaching these radiating elements to the body to be cooled or their relative arrangement thereon is merely a matter of judgment or convenience and constitutes no part of my present invention. The radiating elements may be alternated both as to rows and as to axial positions, as shown in Figs. 8 and 9, or they may be placed in rows continuous and all alike, as indicated in Fig. 13, the positioning and spacing of the radiating elements in any given case being wholly a matter of judgment. If, for example, the surface, whether plain or curved, be vertical, it is usually preferable to place the radiating elements in vertical rows with the corrugated sides *c c* vertical and the openings *f* one directly over another, so that ascending currents of air may readily traverse all the spaces *f*, and so rapidly convey away the heat-waves emitted by the radiating sides or wings *c c*, or if the surface provided with the radiating elements be horizontal it may be desirable in some cases to alternate the axial positions of the radiators, so that varying horizontal currents of air may readily find way through the differently-positioned parts.

What I claim as my invention, and desire to secure by Letters Patent, is—

1. A hollow radiating element for attaching to a larger body, having a radiating portion and a cylindrical portion, a larger body having an indentation for receiving said cylindrical portion, and a ring in said cylindrical portion, and a part coacting with the ring to spread the latter.

2. A hollow radiating element for attaching to a larger body, having a radiating portion and a cylindrical portion, a larger body having an indentation for receiving said cylindrical portion, and a ring divided at one side in said cylindrical portion, and a ball to enter said ring, the diameter of the ball being greater than the internal diameter of the ring.

In witness whereof I have hereunto set my hand, this 12th day of June, 1905, in the presence of two subscribing witnesses.

FREDERICK SAGER.
